UNITED STATES PATENT OFFICE.

WILLIAM CHARLES TODD AND JAMES WILLIAM POMEROY, OF VICTORIA, BRITISH COLUMBIA, CANADA.

WATER SPRINKLER.

Application filed November 3, 1925. Serial No. 66,570.

To all whom it may concern:

Be it known that we, WILLIAM C. TODD and JAMES W. POMEROY, citizens of the Dominion of Canada, residing at Victoria, in the Province of British Columbia, Canada, have invented certain new and useful Improvements in Water Sprinklers, of which the following is a specification.

This invention relates to a water sprinkler such as is used for irrigating purposes, and belongs to that class wherein an outwardly directed main jet or jets is slowly rotated to project its spray beyond that of a reaction sprinkler rotatable on the same axis.

15 The improvements are directed to the means whereby the main sprinkler head is slowly rotated by small increments from the rotation of the reaction sprinkler head.

The invention is fully described in the 20 following specification, reference being made to the drawings by which it is accompanied, in which:

Fig. 1 is an elevation and part section of the sprinkler.

25 Fig. 2 is a sectional elevation showing the driving connection between the reaction sprinkler tubes and a main sprinkler tube in the direction of the arrow 2 in Fig. 1, and

30 Figs. 3 and 4 show in similar views alternative driving connections.

In these drawings 2 represents a stand pipe to which a supply of water under pressure is delivered from a water service.

35 On this stand pipe 2 is secured a nipple 3 having a shouldered reduction adapted to receive the collar 5 of a short hollow stem 6. On the upper end of this stem 6 is secured a cross 7 from the horizontal components of 40 which extend each way the main sprinkling pipes 8, the outer ends of which are upwardly turned to the desired angle of projection and have a cap 9 apertured to deliver the desired spray.

45 In the upper end of the cross 7 which is in alignment with the stand pipe is a nipple 10 having a shouldered reduction at 11 adapted to form a seat for the collar 12 of a hollow stem 13 rotatable in the nipple 10.

50 On the outwardly projecting end of this stem 13 is secured a T 14 from which extends each way the horizontally disposed pipes 15 of a reaction sprinkler, the ends of which are upwardly and backwardly

turned and are capped with apertured 55 ends 16.

The stem 6 of the main sprinkler 7, 8, 9 is thus freely rotatable in the bearing 3 and the collar 5 of that stem constitutes an effective seal preventing the escape of the 60 water past the bearing, without any requirement of packing or a ground joint: And so with the stem 13 of the reaction sprinkler 14, 15, 16 which is independently rotatable in the bearing 10 which is secured to and 65 rotatable with the main sprinkler 7, 8, 9 and its stem 6, and the ends of the tubes 15 being backwardly turned this sprinkler is rotated by the reaction of its escaping 70 jets.

Secured on one of the arms 8 of the main sprinkler to project upward from it is a member 17 in the upper end of which is pivotally mounted at 18 a lever 19. This lever 19 is checked in the upright position and is 75 counter-weighted at 20 to normally maintain the end 21 in the path of the tubes 15 of the reaction sprinkler and to offer a yielding resistance to movement off the check.

In the upright position it will be engaged 80 by the tubes 15 of the reaction sprinkler, which engagement, owing to the yielding resistance, will move the main sprinkler 7, 8, 9 through a fraction of its rotation in the bearing 3 and at the same time will allow 85 the tubes 15 to pass.

Figure 2 shows a counterweight 20 as affording this yielding resistance. In Figure 3 it is afforded by a spring 21 from a pin 90 projecting from the lever 19 to one projecting from the hub of the upwardly projecting member 17, and Figure 4 shows the yielding resistance as offered by a spring 22 secured in and upwardly projecting from 17 with a sleeve 23 slidable between an 95 upward projection 24 from 17 and the spring 22 whereby the tension on that spring may be adjusted.

The substance of the invention resides in the simple provision whereby a relatively 100 small rapidly rotating reaction sprinkler 14, 15, 16 may be applied to rotate about the same axis as the main sprinkler head 7, 8, 9, throwing a larger quantity of water and throwing it radially outward, that is, not 105 checked by the requirement of the jets being directed backward to impart rotation.

The parts are simple to manufacture and

to maintain and leakage past the bearing is effectively prevented without any requirement of gland packing or ground joints to impede rotation to add to its expense.

5 Having now particularly described our invention, we hereby declare that what we claim as new and desire to be protected in by Letters Patent, is:

1. A water sprinkler of the class described, 10 comprising in combination an upright pipe to which a supply of water under pressure is delivered, a hollow stem rotatably mounted in the upper end of the pipe from which stem a tubular arm laterally projects with a 15 nozzle directed outward and upward from it to constitute the main sprinkler, a second hollow stem rotatably mounted in the upper end of the first named stem from which second stem the arms of a reaction operating 20 sprinkler project, and a yielding projection secured on one of the sprinklers to engage an adjacent part of the other sprinkler whereby the rotation of the reaction sprinkler will move the main sprinkler through a 25 fraction of its rotation on each engagement.

2. A water sprinkler of the class described, 30 comprising the combination with an upright pipe to which a supply of water under pressure is delivered, of a hollow stem rotatably mounted in the upper end of the pipe from which stem a tubular arm laterally projects with a nozzle directed outward and upward from it to constitute the main sprinkler, a second hollow stem rotatably mounted in the 35 upper end of the first named stem from which second stem the arms of a reaction operating sprinkler project, and a yielding projection from an arm of one of the sprinklers to engage a corresponding part of the other sprinkler whereby the rotation of the operating sprinkler will move the main sprinkler through a fraction of its rotation on each impact of the yielding projection.

3. A water sprinkler of the class described, 45 comprising the combination with an upright pipe to which a supply of water under pressure is delivered, of a hollow stem rotatably mounted in the upper end of the pipe from which stem a tubular arm laterally projects 50 with a nozzle directed outward and upward from it to constitute the main sprinkler, a second hollow stem rotatably mounted in the upper end of the first named stem from which second stem the arms of a reaction 55 sprinkler project, and means projecting

from one of the tubular arms of the main sprinkler to offer a yielding obstruction to movement of the reaction sprinkler past it, and by which the main sprinkler is moved through a fraction of its rotation on each engagement.

4. A water sprinkler of the class described, comprising the combination with an upright pipe to which a supply of water under pressure is delivered, of a hollow stem rotatably 65 mounted in the upper end of said pipe from which stem a tubular arm laterally projects with a nozzle directed outward and upward from it to constitute the main sprinkler, a second hollow stem rotatably mounted in 70 the upper end of the first named stem from which second stem the arms of a reaction operating sprinkler project, and a yielding resistance secured on the arm of the main sprinkler and projecting upward from it to 75 engage a passing part of the operating sprinkler whereby the arm of the main sprinkler will be moved through a fraction of its rotation for each rotation of the reaction sprinkler.

5. A water sprinkler of the class described, 80 comprising the combination with an upright pipe to which a supply of water under pressure is delivered, of a reducing nipple secured on the upper end of the pipe, said 85 nipple bored as a bearing with a shoulder at the reduction, a hollow stem rotatably mounted in the bearing of the nipple with a collar seating in the shouldered reduction, said stem projecting beyond the upper end 90 of the nipple, tubular arms secured to and projecting horizontally from the stem, through which arms the main supply of 95 sprinkling water is delivered, a second reducing nipple secured to the upper end of the hollow stem and in axial alignment with it, a second hollow stem rotatably mounted in this reducing nipple, said stem having a collar seated on the shouldered reduction of the nipple, a reaction sprinkler secured to 100 and rotatable with the second named hollow stem, and means for moving the main sprinkler through a fraction of its rotation each time a tube of the reaction sprinkler passes a tube of the main sprinkler.

In testimony whereof we affix our signatures.

WILLIAM CHARLES TODD.
JAMES WILLIAM POMEROY.
